The ornamental design for a blood sugar machine, as shown and described.

DESCRIPTION

FIG. 1 is a perspective view of a blood sugar machine showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 is a perspective view of the blood sugar machine viewed from another direction.

The broken lines illustrate portions of the blood sugar machine that form no part of the claimed design.
